HOT-GAS RECIPROCATING APPARATUS

Roelf Jan Meijer, Emmasingel, Eindhoven, Netherlands, assignor to North American Philips Company, Inc., New York, N.Y., a corporation of Delaware

Filed Mar. 3, 1964, Ser. No. 349,113

Claims priority, application Netherlands, Mar. 11, 1963, 290,075

6 Claims. (Cl. 62—6)

The invention relates to a hot-gas reciprocating apparatus comprising one or more cylinder spaces in each of which a displacer and a piston are adapted to reciprocate with a relative phase difference so as to vary the volumes of an expansion space and a compression space. In the operation of the machine, these spaces have different mean temperatures and communicate with each other by means of a first heat exchanger (heater), a regenerator and a second heat exchanger (cooler). The regenerator is subdivided into a plurality of regenerator elements arranged parallel to each other, while the second heat exchanger is subdivided into a number of parallel-arranged elements equal to that of the regenerator.

For the purpose of this specification, the term "hot-gas reciprocating apparatus" is defined to include not only a hot-gas engine, but also a cold gas refrigerator and a heat pump operating according to the reversed hot-gas engine principle.

In known apparatus of the said kind, the regenerator is arranged with an initial tension in a thin-walled housing which in turn is accommodated in a further housing. This construction suffers from the limitation that, if no further precautions are taken, upon the passage of the working medium through the regenerator alternately in one and in the other direction, the regenerator tends to follow the movement of the medium and strikes the end faces of the housing. This is due to the fact that the regenerator can exhibit dimensional differences with respect to the housing in which it is accommodated, which differences are further enlarged by the temperatures occurring in the regenerator, while the medium flowing through the regenerator tends to compress the regenerator. In order to prevent the regenerator from moving in its housing, it has already been suggested to provide the housing with a spring which resiliently holds the regenerator in the housing. This impairs the appearance and simplicity of the construction, while this spring increases the dead space. This adversely affects the efficiency of the apparatus.

The invention has for its object to obviate the above disadvantages and the apparatus is characterized in that each element of the second heat exchanger is accommodated together with a regenerator element in one housing, the axial inner dimension of the housing in which an element of the second heat exchanger, which heat exchanger is constructed rigidly in the axial direction, and the associated elastically compressible regenerator element are accommodated, being smaller than the sum of the axial dimensions of the two elements when disassembled.

In the construction in accordance with the invention, the regenerator is consequently compressed more strongly while being mounted in the housing, while after mounting the regenerator filler material itself ensures that the regenerator does not move in the housing.

An advantageous embodiment of the hot-gas reciprocating apparatus in accordance with the invention is characterized in that each regenerator element consists of a filler material accommodated in a further housing which, at its side facing the associated element of the second heat exchanger, embraces a rim of the said element in a

manner such that the further housing accommodated in a housing and the said element of the second heat exchanger are relatively movable under the influence of axial forces.

A favourable embodiment of the hot-gas reciprocating apparatus in accordance with the invention, in which this apparatus comprises more than one cylinder space, is characterized in that the housings associated with a given cylinder space, in each of which a regenerator element and an element of the associated second heat exchanger are accommodated, are arranged in two groups around the cylinder space concerned, one group being situated on one side and the other group on the other side of the plane passing through the longitudinal axes of the cylinder space concerned. This embodiment is of particular importance when the hot-gas reciprocating apparatus is to be accommodated in a small space. The distance between the longitudinal axes of two adjacent cylinder spaces can then be smaller than in the case of a regular arrangement of the cooler-regenerator units around the cylinder spaces.

An even more compact structure of the hot-gas reciprocating apparatus in accordance with the invention is characterized in that, while the housings of the two groups are situated pairwise diametrically opposite each other, the two housings of each group farthest remote from each other are at different distances from the plane passing through the longitudinal axes of the cylinder spaces.

A further favourable embodiment of the hot-gas reciprocating apparatus in accordance with the invention, in which one or more pipes of the first heat exchanger are connected to each of the housings, the other ends of these pipes being connected to an annular duct to which further pipes are connected through which this duct communicates with the expansion space, is characterized in that each of the pipes of the first heat exchanger contains an expansion member which imparts a certain axial flexibility to these pipes. As a result the temperature stresses occurring in the structure are absorbed by the expansion member.

According to a further favourable embodiment, the expansion member is constituted by a portion of the pipe which extends transversely to the longitudinal axis of the relevant cylinder space.

In order that the invention may be readily carried into effect, embodiments thereof will now be described, by way of example, with reference to the accompanying drawings, in which:

FIGS. 1 and 2 are an axial section and a cross-section taken on the line II—II, respectively, of a hot-gas reciprocating apparatus in accordance with the invention only that part of the apparatus being shown which consists of the cylinder and the piston and displacer adapted to reciprocate therein, and of the first heat exchanger and the second heat exchanger with the interposed regenerator,

FIGS. 3a and 3b show a cooler-regenerator unit in the demounted state and in the mounted state, respectively.

FIG. 4 shows diagrammatically a possible arrangement of the cooler-regenerator units around the cylinder spaces.

FIGS. 5 and 6 are an elevation and a cross-section taken on the line VI—VI respectively, of a further embodiment of a hot gas reciprocating apparatus.

In the embodiment shown in FIGS. 1 and 2, reference numeral 1 denotes the cylinder wall the upper side of which terminates in an end face 2. Pipe portions 3 of the heater open into the conical part of the head face. The upper ends of these pipe portions 3 are connected to an annular duct 4. This annular duct 4 constitutes the connection between the pipe portions 3 and heater pipe

portions 5. For the sake of clarity, only two sets of the heater pipes 3 and 5 are shown; in actual fact together they enclose a cylindrical space 6 which serves as a combustion chamber. A burner is placed in or above this space.

With the aid of means (not shown), a displacer 8 and piston 9 are adapted to reciprocate in the cylinder 1. The heater pipes 5 are also connected to the cooler-regenerator units 10. The structure of these units will be described more fully with reference to FIGS. 3a and 3b. Through a connection pipe 11, the cooler-regenerator units 10 communicate with the cylinder 1. As is apparent from the figures, the heater pipes 5 are provided with a portion 12 extending transversely to the longitudinal axis of the cylinder. This heater pipe portion 12 imparts a certain flexibility to the heater pipes 5, so that, when the distance between the upper ends of the cooler units 10 and the annular duct 4 is increased as a result of temperature differences, no fracture will occur in the apparatus.

FIG. 3a shows a cooler-regenerator unit comprising a cooler portion 13 and a regenerator portion 14. The cooler portion 13 comprises a plurality of pipes 15 the lower ends of which are secured in a flange plate 16 and the upper ends in a plate 17 the upper side of which is provided with a flanged rim 18. The regenerator portion 14 comprises a thin-walled housing 19 which is closed at its upper end by a plate 20 provided with a plurality of holes 21. The housing 19 further comprises filler material 22. This filler material may consist, for example, of a plurality of stacked gauzes. The filler material 22 is bounded on its lower side by a sieve plate 23. The lower end of the housing 19 is crimped over the flanged rim 18. The filler material 22 and the sieve plate 23 are accommodated in the housing 19 so that a slight movement in the axial direction with respect to the housing is possible. The housing 19 can slide over the flanged rim 18. In the demounted state shown in FIG. 3a, the assembly of cooler and regenerator has an axial length A₁.

FIG. 3b shows the cooler-regenerator unit in the mounted state. The cooler-regenerator unit is accommodated in a housing 40 to the upper end of which one or more heater pipes 5 are connected. The plate 20 of the regenerator 14 engages the shoulder 24 of the housing 40. The housing 40 is closed at its lower end by a closing member 25 which in the embodiment shown in FIG. 3b is soldered in the housing. The closing member 25 may also be connected to the housing 40 by a screwed connection or in a different manner. The cooler-regenerator unit 13, 14 is enclosed between the shoulder 24 and the upper edge of the closing member 25, the distance between the shoulder 24 and the upper edge of the closing member 25 having a dimension A₂ which is smaller than the length A₁ of the cooler-regenerator unit in the demounted state. As a result of this smaller dimension A₂, the filler material 22 is slightly compressed, while the housing 19 has slid over the rim 18, so that, as is apparent from figure, there is a certain amount of clearance between the crimped edge of the housing 19 and the lower surface of the rim 18. An inlet 26 and an outlet 27 for the cooling liquid also communicate with the housing 40. Consequently, the cooling liquid flows around the pipes 15, while O-shaped rings 28 ensure satisfactory sealing. The closing member 25 has a recess 30 through which the pipes 15 communicate with the connection pipe 11 which connects the cooler-regenerator unit to the space in the cylinder 1.

The compression of the filling mass 22 can be increased or decreased at will by interposing one or more rings between the upper edge of the closing member 25 and the plate 16 of the cooler 13. It should be appreciated that these rings may also be provided between the shoulder 24 and the plate 20 of the regenerator 14.

FIG. 4 shows diagrammatically an embodiment of a

hot-gas reciprocating apparatus in which the cooler, regenerator units 10 are arranged in two groups of three, one group on either side of the plane passing through the longitudinal axes of the cylinder spaces. The figure 5 clearly shows that the distance B between the longitudinal axes of the two cylinders is smaller than in case the units 10 are arranged arbitrarily around the cylinders, as shown in FIGS. 1 and 2. A further decrease of this distance is obtained when the units 10 are arranged 10 around the cylinders in the manner shown in FIGS. 5 and 6. In these figures, two cylinders 31 and 32 are shown. Two groups of regenerator-cooler units are arranged around the cylinder 31. The regenerator-cooler units 33, 34, 35 are located on one side of the plane 15 passing through the longitudinal axes of the cylinders 31 and 32, whilst the other group of regenerator-cooler units 36, 37, 38 co-operating with cylinder 31 are located on the other side of that plane. It is apparent from the drawing that the regenerator-cooler units of 20 each group most remote from each other are located at different distances from the plane passing through the longitudinal axes of the cylinders. The units 33 and 38 located diametrically opposite each other are closer to the plane passing through the longitudinal axes of the cylinders than the units 35 and 36 likewise located diametrically opposite each other. The same holds for the units connected with the cylinder 32. In this manner, an extraordinarily compact, short structure of a hot-gas reciprocating apparatus is obtained.

Finally, it is again clearly apparent from FIG. 5 that the heater pipes 5 for part of their lengths extend transversely to the longitudinal axis of the cylinder with which they co-operate. From this figure also appears the advantage that the length of the transversely extending portions of the heater pipes is greater according as the heater pipe has a larger dimension between the point at which it communicates with the annular duct 4 and its connecting point to the cooler-regenerator unit.

What is claimed is:

40 1. A hot-gas reciprocating apparatus comprising at least one cylinder having a compression space and an expansion space, a displacer and a piston adapted to reciprocate in said cylinder with a relative phase difference and to vary the volumes of said compression and 45 expansion spaces, said spaces being at different mean temperatures during operation of said apparatus, means connecting said spaces and including a heater, a cooler and a regenerator, said regenerator being subdivided into a plurality of substantially parallel-arranged regenerator elements, resiliently compressible in the axial direction, said cooler also being subdivided into a plurality of substantially parallel-arranged axially rigid elements equal in number to the number of said regenerator elements, a main housing, each element of said cooler being accommodated together with a regenerator element in said housing, the axial inner dimension of the housing containing said rigid cooler elements and compressible regenerator elements being smaller than the sum of the axial dimensions of any of said cooler elements and corresponding regenerator elements in their demounted state.

60 2. A hot gas reciprocating apparatus as claimed in claim 1 wherein each regenerator element is constituted of a filler material and said cooler element is provided with a rim, a second housing enclosing said regenerator element, said second housing on its side facing the associated cooler element embraces said rim on the cooler element in a manner such that said second housing located in said main housing and cooler element are movable with respect to each other under the influence of axial forces thereon.

65 3. A hot gas reciprocating apparatus as claimed in claim 1 wherein regenerator elements and associated cooler elements are arranged in two groups around said cylinder space, one group being located on one side

and the other group on the other side of the plane passing through the longitudinal axis of said cylinder space.

4. A hot gas reciprocating apparatus as claimed in claim 3 wherein the housings of said two groups are located pairwise diametrically opposite to each other while the housings of each group most remote from each other are located at different distances from the plane passing through the longitudinal axes of said cylinder spaces.

5. A hot gas reciprocating apparatus comprising at least one cylinder having a compression space and an expansion space, a displacer and a piston adapted to reciprocate in said cylinder with a relative phase difference and to vary the volumes of said compression and expansion spaces, said spaces being at different mean temperatures during operation of said apparatus, means connecting said spaces and including a heater, a cooler and a regenerator, said regenerator being subdivided into a plurality of substantially parallel-arranged regenerator elements, resiliently compressible in the axial direction, said cooler also being subdivided into a plurality of substantially parallel-arranged axially rigid elements equal in number to the number of said regenerator elements,

5 a main housing, each element of said cooler being accommodated together with a regenerator element in said housing, the axial inner dimension of the housing containing said rigid cooler elements and compressible regenerator elements being smaller than the sum of the axial dimensions of any of said cooler elements and corresponding regenerator elements in their demounted state, an annular duct, a plurality of pipes being part of said heater, one end of each of said pipes being in communication with said housing, the other end of each of said pipes being in communication with said annular duct, said annular duct being provided with further ducts for communication with said expansion space, and each of said pipes of said heater including an expansion member.

10 15 6. A hot gas reciprocating apparatus as claimed in claim 5 wherein said expansion member is constituted by a portion of the pipe extending transversely to the longitudinal axis of said cylinder space.
